COMBINATION SUBSONIC, SUPERSONIC AND
NONSONIC BOOM AIRCRAFT

Kenneth E. Olson, 300 W. Mullan, Waterloo, Iowa

Filed Oct. 9, 1964, Ser. No. 82,122

Term of patent 7 years

(Cl. D71—1)

FIGURE 1 is a perspective view of the aircraft in subsonic flight position;

FIGURE 2 is a right side elevational view of FIG. 1 to a different scale;

FIGURE 3 is a top view of FIG. 1;

FIGURE 4 is a front view of FIG. 1;

FIGURE 5 is a rear view of FIG. 1;

FIGURE 6 is a top view of the aircraft with the wings, elevator and rudder medial the subsonic and supersonic flight position;

FIGURE 7 is a perspective view of the aircraft in supersonic flight position;

FIGURE 8 is a right side elevational view of FIG. 7 to a different scale;

FIGURE 9 is a top view of FIG. 7;

FIGURE 10 is a front view of FIG. 7; and

FIGURE 11 is a back view of FIG. 7.

I claim:

The ornamental design for a combination subsonic, supersonic and nonsonic boom aircraft, substantially as shown and described.
